(57) **CLAIM**

The ornamental design for a crimping insert, as shown and described.

DESCRIPTION

FIG. 1 is a rear elevational view of a crimping insert according to a first embodiment of the present invention. FIG. 2 is a bottom plan view of the crimping insert of FIG. 1.

FIG. 3 is a front elevational view of the crimping insert of FIG. 1.

FIG. 4 is a perspective view of the crimping insert of FIG. 1.

FIG. 5 is a left side elevational view of the crimping insert of FIG. 1.

FIG. 6 is a right side elevational view of the crimping insert of FIG. 1.

FIG. 7 is a top plan view of the crimping insert of FIG. 1. FIG. 8 is a rear elevational view of a crimping insert according to a second embodiment of the present invention. FIG. 9 is a bottom plan view of the crimping insert of FIG. 8.

FIG. 10 is a front elevational view of the crimping insert of FIG. 8.

FIG. 11 is a perspective view of the crimping insert of FIG. 8.

FIG. 12 is a left side elevational view of the crimping insert of FIG. 8.

FIG. 13 is a right side elevational view of the crimping insert of FIG. 8.

FIG. 14 is a top plan view of the crimping insert of FIG. 8. FIG. 15 is a rear elevational view of a crimping insert according to a third embodiment of the present invention. FIG. 16 is a bottom plan view of the crimping insert of FIG. 15.

FIG. 17 is a front elevational view of the crimping insert of FIG. 15.

FIG. 18 is a perspective view of the crimping insert of FIG. 15.

(Continued)

FIG. 19 is a left side elevational view of the crimping insert of FIG. 15.

FIG. 20 is a right side elevational view of the crimping insert of FIG. 15.

FIG. 21 is a top plan view of the crimping insert of FIG. 15.

FIG. 22 is a rear elevational view of a crimping insert according to a fourth embodiment of the present invention.

FIG. 23 is a bottom plan view of the crimping insert of FIG. 22.

FIG. 24 is a front elevational view of the crimping insert of FIG. 22.

FIG. 25 is a perspective view of the crimping insert of FIG. 22.

FIG. 26 is a left side elevational view of the crimping insert of FIG. 22.

FIG. 27 is a right side elevational view of the crimping insert of FIG. 22; and,

FIG. 28 is a top plan view of the crimping insert of FIG. 22. In FIGS. 22-25 and 28, portions depicted in broken lines represent boundaries of the claimed design and are not part of the design sought to be patented.
